UNITED STATES PATENT OFFICE.

OLE A. JOHNSON, OF CLEVELAND, OHIO.

TENNIS-RACKET.

1,188,940.

Specification of Letters Patent. Patented June 27, 1916.

Application filed September 25, 1915. Serial No. 52,597.

To all whom it may concern:

Be it known that I, OLE A. JOHNSON, a citizen of the United States, residing at Cleveland, in the county of Cuyahoga and State of Ohio, have invented a certain new and useful Improvement in Tennis-Rackets, of which the following is a full, clear, and exact description.

This invention relates to an improvement in tennis rackets, the object of the invention being to provide a stringing of the racket whereby strength is imparted to the net of strings and at the same time provides a means for preventing side slipping or side-wise displacement of the strings,—more particularly those strings adjacent the center of the racket where the hardest usage comes.

Generally speaking, the invention comprises the elements and combinations thereof set forth in the accompanying claims.

Reference should be had to the accompanying drawings forming a part of this specification in which—

Figure 1 is an elevation of a racket embodying a stringing according to my invention; Fig. 2 is an elevation of a portion of the stringing of the racket showing in more detail the embodiment of my invention.

In tennis rackets, as usually constructed, *i. e.*, with an oval or substantially oval head, the center of percussion of the head, or, in other words, that portion of the racket which when brought into contact with a ball gives the greatest effective impulse to the ball, is an area substantially at the central portion of the strings of the racket. Every experienced tennis player seeks to impact the ball at the center of the net of the racket, and this is true not only of direct drives but of all those strokes which involve cutting the ball. The strokes which involve what is termed cutting the ball or imparting a rotating movement as well as a projectile movement to the ball, depend upon the fact that the strings engage with the furry cover of the ball with a slanting impact. These cut strokes, of course, have a tendency to displace the strings of the racket, particularly the longitudinal strings of the racket, and as the racket is used more and more this tendency becomes more pronounced and actually causes a slipping of the strings, which slipping of the strings results in giving the ball less of a twist than is desirable in order to impart the desired amount of cut to the

ball, and makes results uncertain and unpredictable.

Various means have been proposed for preventing slipping of the strings, but so far as I am aware, the particular method which I employ for accomplishing this result is new.

I employ the usual longitudinal strings 1 and the usual transverse strings 2, and in addition to these strings I employ four strings which are numbered respectively 3, 4, 5 and 6. The strings 3 and 4 extend in a diagonal direction across the head of the racket and are parallel to each other. Likewise the strings 5 and 6 extend in a diagonal direction across the racket and are parallel with each other. The strings 5 and 6 extend at an angle with respect to the strings 3 and 4 and at their point of intersection inclose a diamond-shaped area which I have indicated by the reference numeral 7. The strings 3, 4, 5 and 6 are so placed with respect to the usual strings of the racket that the space 7 inclosed is at substantially the center of the racket and comprehends that space upon the strings of the racket which is the area of most effective engagement with the ball, sometimes called the center of percussion of the racket.

The invention may be practised in two ways,—either by making the strings 3, 4, 5 and 6 a continuation of the stringing of the racket or the strings may be put in separately.

When the reinforcing stringing is separate from the regular stringing, I use a single string to effect the desired reinforced stringing. For instance, this string may be fastened by means of a knot at 8 extended through suitable openings in the racket, as indicated by dotted lines at 9; thence extended through the racket as indicated at 10; thence extended through and along the outer edge of the racket as indicated in dotted lines at 11; thence extended through and along the outer edge of the racket as indicated at 12; thence extended through the racket as indicated by dotted lines at 13 and tied in a knot as indicated at 14.

In making the reinforced stringing as a part of the regular stringing of the racket I would preferably make this reinforced stringing as a continuation of the transverse strings 2. It will be understood that all of the transverse strings on the racket are made

of one long string of gut. This string is usually 19 feet long and it requires less than 19 feet to provide the transverse strings of the racket. What is left over of the string 5 could readily be utilized in producing the reinforced stringing without severing the gut.

The continuous stringing of the racket does not produce any better results than where a separate string is used, but is, perhaps, a little cheaper in the manufacturing cost where the racket is being strung originally and restrung than putting in the reinforcing strings as an extra stringing. Of course, the reinforced stringing may readily 15 be applied to a racket already strung, and will produce the desired effect.

There is another advantage incident to the arrangement of the reinforced strings, and that is the fact that the strings in defining 20 the area which is the center of percussion of the racket, enable the player to more readily distinguish this area as he is applying his racket to the ball. This is particularly true when the strings 3 and 4 and 5 and 6 are 25 made of a gut having a color different than the color of the gut forming the main stringing of the racket. This is quite an advantage for reasons which will be obvious.

Having described my invention, I claim: 30 1. In a tennis racket, the combination with a suitable frame, transverse and longitudinal strings secured in the frame of the racket and strings extending diagonally across the frame of the racket, said strings inclosing 35 an area including only a portion of said transverse and longitudinal strings, which comprehends the center percussion of the racket.

2. A tennis racket, comprising a frame, 40 strings extending longitudinally and transversely thereof and woven to form a net, other strings extending across the head of the racket extending diagonally with respect to the first mentioned strings of the racket, 45 the said other strings being woven into the net and inclosing a portion of the net in-

cluding only the said longitudinally and transversely extending strings, which is at the center of percussion of the racket.

3. A tennis racket, comprising a head 50 having a net work of longitudinally and transversely extending strings, two pairs of parallel strings extending across the said netting, said pair of strings extending at an angle to each other and to the strings of the 55 netting, said strings inclosing an area upon the netting including only the said longitudinally and transversely extending strings, which includes the center of percussion of the racket.

4. A tennis racket, comprising a frame having a netting of transversely and longitudinally extending strings, a pair of parallel strings extending across the frame and interwoven with the netting, a second pair 60 of parallel strings extending across the frame and interwoven with the netting, the said pairs of parallel strings intersecting with each other and inclosing a space which includes only a portion of the longitudinally 65 and transversely extending strings, which space includes the center of percussion of the racket.

5. A tennis racket, comprising a frame having a net of longitudinally and transversely extending strings, a single string tied 70 at one point to the frame of the racket extending diagonally across the racket, thence extending along an outer edge of the racket, thence extending across the net of the racket 75 parallel to the direction of the first mentioned string, thence extending along an outer edge of the racket, thence extending transversely of the netting of the racket, thence extending upon an outer portion of 80 the racket, thence extending across the net of the racket parallel to the last mentioned string and then tied to the racket.

In testimony whereof, I hereunto affix my signature.

OLE A. JOHNSON,
Formerly Ole A. J. Thorbjornsen.
